BAG FOR FOLDING CHAIRS

Philip M. Friedlander, New York, N. Y., assignor
to Bertha Friedlander, New York, N. Y.

Application October 17, 1931, Serial No. 569,463

3 Claims. (Cl. 150—52)

My invention relates to bags of the kind used for carrying a number of folding chairs such as chairs used for card parties, by undertakers, and various other uses where the chair is made to fold into compact shape for storage or transportation. It is customary to provide a bag for holding a number of folding chairs in close, parallel relation to facilitate handling of a number of chairs as a unit and to protect the chairs while they are being handled, as well as to provide convenient means for storing the chairs when they are not in use.

One object of my invention is to provide a bag of this type which is simple in construction, inexpensive to manufacture, and which will hold a number of chairs in close, parallel relation with proper protection between the several chairs to prevent them from rubbing against each other. The bag proper is preferably made of a single piece of heavy canvas or duck, although any other fabric may be employed for the purpose. The blank body is so cut that a single piece of material may be used to form the four sides as well as the bottom of the bag, the bottom being made of more than one thickness at the portions where the wear is greatest; and the blank also provides material for four flaps at the top of the bag adapted to be folded in over the tops of the chairs. In addition, I provide a number of fabric partitions for maintaining the chairs separated from each other and I also provide means for holding up the top edges of the partitions in order that they will not sag down and permit the tops of the chairs to rub against each other.

Another object of the invention is to provide a continuous strip of binding tape around the edges of all of the top flaps, so that there will be no tendency for the bag to tear at the corners of the several flaps.

Another object of the invention is to provide false seams along three of the vertical edges of the bag and a real seam for the fourth edge, so that while the bag is made of one piece it will have a tendency to shape up in rectangular form the same as if it were made of four separate pieces attached together.

Another object of the invention is to provide suitable straps for holding the top flaps folded over the chairs and also to provide a strap passing around the entire bag to hold it closed and to form a suitable means for carrying the bag and its contents as a unit. Other advantages will be set forth in the following description of my invention.

In the drawings forming part of this application,

Figure 1 is a perspective view of a bag containing my invention and showing the same in closed position ready to be carried.

Figure 2 is a cross sectional view thereof,

Figure 3 is a horizontal sectional view,

Figure 4 is a perspective view of the upper portion of the bag with the flaps partially folded and with one flap broken away to show the unfolded portion,

Figure 5 is a perspective view of the upper portion of the bag before the flaps are folded,

Figure 6 is a fragmentary view showing the method of forming the multi-ply bottom wall and the method of attaching the partitions to the bag, and

Figure 7 is a face view of a blank from which the bag may be made of one piece.

In Figure 7 I have shown a blank 1 from which the one piece bag may be formed. The dotted lines in this figure indicate the lines on which the blank will be folded when assembled. The blank 1 is cut from a single piece of fabric and contains two sections 2, 3 of similar shape and dimensions which will form the side walls of the bag when the same is made up. It also contains two sections 4, 5 which lie next to the sections 2, 3 and which will form the ends of the bag when the same is made up. The bottom of the blank is preferably provided with a section 6 contiguous with one of the sections 2 and which will form the bottom wall of the bag. The two sections 7, 8 contiguous with the end wall sections 4, 5 will be folded within the section 6 and form reinforcements for the bottom wall of the bag adjacent the ends.

The upper portion of the blank in Figure 7 is provided with two sections 9, 10 having rounded top edges which sections are adapted to form two of the flaps and they are contiguous to the side wall sections 2, 3. Adjacent the sections 9, 10 there are narrower sections 11, 12 also having rounded tops and contiguous to the end sections 4, 5 respectively, and they are to form two flaps for the top of the bag.

Either before the bag is made up into rectangular form or after a continuous piece of tape 13 is applied to the blank to overlap the top edge, and this tape runs continuous around the curved top edges of the four flap sections 9, 10, 11, 12 so that this tape, which serves to bind the edge and protect the same, can be traced as shown in Figure 5 as a continuous member extending around the top edges of all four flaps. The blank is provided with lines of stitches 14, to form false

seams along the three lines 15, 16, 17 as shown in Figure 3 so that the material will take a natural bend and fall into rectangular shape.

The opposite ends of the blank are brought together and are secured to each other by a line of stitches 18 forming a real seam on the fourth corner or edge of the bag. Instead of forming the bag of four separate pieces with real seams at each corner, it is less expensive and more dependable to apply the false seams to three of the edges in order to create the desired shape.

The bottom member 6 is turned so as to extend across the bottom of the bag and the two bottom members 7 and 8 are turned up to lie under the member 6 for the purpose of reinforcing the ends of the latter and when all three of these members 6, 7 and 8 are stitched together and to the vertical walls of the bag they form a reinforced and closed bottom. The members 6, 7 and 8 may be conveniently turned up in a horizontal position at the time the ends of the blank are being stitched along the line 18.

The partitions for separating the several parallel chairs placed in the bag are formed as follows: Each partition consists of a wall of fabric 19 with their ends stitched as shown at 20 to the interior of the end walls 4 and 5 of the bag so that they lie in vertical positions inside the bag and are separated from each other approximately the thickness of the folded chair. The bottoms of these walls may be turned and secured to the bottom wall of the bag by means of the lines of stitches 21 shown in Figure 3.

To protect the corners of the dividing walls I have secured strips of binding material 22 across the interior of the bag lines of stitches 23 so that these strips pass across the corners of the several partitions 19 and serve to protect these corners from being torn away from the bag as the chairs are placed into and removed from the several pockets of the bag.

I have shown five dividing walls 19 in the drawings but it will be understood that any other number of such walls may be provided. The number of such walls indicated in the drawings, divides the interior of the bag into six rectangular compartments 24 each one adapted to hold a folded chair. The upper edge of each dividing wall 19 is strengthened and protected by a strip 50 of binding tape 25 which is folded over the edge of the walls and secured thereto by a line of stitches. Near the middle of each dividing wall, and just below the binding tape 25 there is a slot 26 cut through the wall. There is a strap 27 having one end secured as by stitching, to one of the side walls of the bag adjacent the plane of the tops of the several dividing walls, and this strap is adapted to be passed through the several slots 26 of the dividing walls and to have its free end tied to a loop 28 secured to the other side wall of the bag.

There is another strap 29 attached to the outside of the bag, as by stitches 30, and this strap is adapted to be passed over the two end flaps 11, 12 when they have been folded down, and to be tied to a loop 31 which is secured to the opposite end of the bag adjacent the flap 4.

There is a strap 32 adapted to encircle edge-wise around the entire bag and this strap passes through a loop 33 attached to the outer side of one of the flaps 3 and it also passes through loops 34 on one of the side walls of the bag. This strap is provided with a buckle 36 for securing the ends together after the bag has been closed. The portion of the strap lying between the loops 34

is adapted to form a handle by means of which the bag and its contents may be conveniently carried.

To receive the chairs, the bag is opened up, as shown in Figure 5, and it will be understood that the flaps may be turned down against the outside of the bag if desired. Folding chairs may be inserted into the tops of the several compartments 24 and allowed to slide down until the legs of the chairs rest on the reinforced bottom of the bag. One chair will be inserted in each of the compartments 24 so that there is a dividing wall 19 between the several chairs to prevent them from coming into contact with each other. After the several chairs have been inserted into these pockets, the strap 27 is threaded through the several slots 26 of the dividing walls and the free ends tied to the loop 28. This strap will extend across the several pockets 24 above the tops of the chairs and it will serve the purpose of preventing the upper portions of the pockets from sagging down and permitting the tops of the chairs to rub against each other. The bag being more or less flexible, this strap is desirable to prevent the chairs from rubbing against each other as they might if the dividing walls were to sag near the tops of the chairs. The next operation is to turn down the two top end flaps 4, 5 as shown in Figure 4, so that they extend across the tops of the chairs. The strap 29 is then carried across the two flaps 4, 5 and the free end tied to the loop 31. This secures the two flaps 4, 5 in folded position. The next operation is to fold the flaps 9, 10 over the flaps 4, 5 to the position shown in Figure 1, these flaps 9, 10 being sufficiently wide to overlap each other. After the bag has thus been completely closed, the strap 32 will be in the position shown in Figure 1 so that it extends entirely around the bag, including the folded top flaps.

The outer strap may now be tightened to hold the bag completely closed, and this strap may be conveniently gripped between the two securing loops 34 to form a handle for carrying the bag and its contents.

The bag being made of a single piece, it is cheaper and more durable than if made of separate pieces stitched together. The top flaps are formed integral with the blank which is the simplest method of making them, and the binding tape 13 not only protects the edges of these several flaps but also prevents the bag from tearing at the lower corners of the several flaps. The real seam and the false seams cause the blank to fall into rectangular shape so that it is convenient to place the chairs in and remove them from the bag. The bottom of the bag which is subject to the greatest wear, is reinforced because of the double ply formed by the overlapping sections 6, 7 and 8. It is two plies thick at the ends of the bag. The folding chairs ordinarily have legs spaced apart so that they rest only on the portions of the bottom which are reinforced by the sections 7 and 8 and it is not necessary that the portions of the bottom wall between the reinforcement 7 and 8 be more than a single thickness, provided, of course, folding chairs are the only articles to be stored in the bag.

The flaps 4, 5 are securely held in folded position by the strap 29 and the dividing walls are supported at the top by the strap 27. The outer strap 32 which encircles the whole bag secures all of the flaps in folded position and this strap is retained on the bag by the several loops 33, 34, 35.

Having described my invention, what I claim is:

1. A bag of the character described, comprising a body formed of side and end walls constituting a rectangular body, partitions secured within the bag and extending across the same to divide the interior into a plurality of parallel compartments, said dividing walls having apertures near their upper ends and a strap member connected at one end with a wall of the bag and adapted to be threaded through said apertures of the partitions and adapted to have its free end secured to another wall of the bag for the purpose of preventing said dividing walls from sagging below the tops of articles disposed in said compartments. 80

2. A bag of the character described, comprising a single body blank of fabric having its opposite ends secured together by a real seam and having false seams extending along said blank at different positions to effect, in connection with said real seam, the shaping of said bag into a rectangular receptacle having side and end walls, partitions formed of sheets of fabric arranged in said receptacle and having opposite ends connected with the walls of said receptacle whereby said par- 85
